UNITED STATES PATENT OFFICE

EDWARD H. LANIER, OF COVINGTON, KENTUCKY

AEROPLANE

Application filed November 19, 1930. Serial No. 496,725.

My present invention relates to the art of aerial navigation, and particularly to aeroplanes of the kind disclosed in my Patents No. 1,750,529, issued March 11, 1930 and No. 5 1,779,005, issued October 21, 1930.

In the practical development of the aeroplanes disclosed in my said Letters Patents I have found by experiments and tests that the lifting power of the vacuum chamber exceeded my expectations, and I have further 10 found that an aeroplane can be designed utilizing the principle of the vacuum chamber lift in which the wings can be wholly eliminated or reduced to dwarf wings, i. e., wings 15 of little lifting power but of sufficient area to serve as supports for the ailerons. It is therefor a principal object of my invention to provide an aeroplane which has little or no wing area and yet possesses the principal advantages possessed by the planes of my 20 patents aforesaid.

Further, it is an object to provide an aeroplane with a vacuum chamber having dihedral flares extended laterally sufficiently to 25 serve in place of wings entirely or substantially.

Further, it is an object to provide such an aeroplane with dwarf wings, for example, which may extend at a level below that of the 30 lateral flares so as to support the ailerons usually employed in aeroplanes.

Other objects will in part be obvious and in part be pointed out hereinafter.

To the attainment of the aforesaid objects 35 and ends, the invention still further resides in the novel details of construction, combination and arrangement of parts, all of which will be first fully described in the following detailed description, then be particularly pointed out in the appended claims, reference being had to the accompanying drawings, in which:—

Figure 1 is a perspective view of my present invention showing the same without the 45 usual wings.

Figure 2 is a side elevation thereof.

Figure 3 is a front elevation thereof.

Figure 4 is a perspective view of my present invention showing the same provided 50 with dwarf wings.

In the drawings I have illustrated my invention as applied to an open cockpit type of plane, although it is obvious that the invention may also be applied to cabin types, as indicated in my patents aforesaid. 55

Referring now to the accompanying drawings, it will be observed that 1 represents the body of the aeroplane, which may be of any approved construction, the open cockpit type fuselage being illustrated for the purposes of 60 this application.

The front landing gear is indicated by 2 and the tail skid by 3, while the usual tail rudders and elevators are indicated by the numeral 4. The propeller is indicated by 65 the numeral 5. In open cockpit type machines there are openings provided at 6 and 7 for the passengers and aviator, these openings being provided with side ports, if desired, or the aviator may simply step over the 70 top of the fuselage into the openings provided. All of the aforesaid structure may be of any approved type, or in lieu of the open cockpit type of fuselage shown the cabin type, 75 such as indicated in my prior patents, may be used.

Extending upwardly along the top of the body is a fin or longitudinal structure 8, the side walls of which extend upwardly and laterally to merge with the under walls of 80 the vacuum chamber that is located above the body 1 and united to it by the fin or longitudinal structure 8. At the front the fin 8 has an upwardly and forwardly inclined wall 9 from which extends upwardly and 85 backwardly a wall 10, the walls 9 and 10 constituting a nose of the fin and vacuum chamber. The vacuum chamber includes the central major portion 12 and the lateral portions 13, the latter being contained in a part 90 of the lateral flares 11. The spread across the lateral flares from side to side is sufficient so that the vacuum chamber structure, i. e., the structure supported by the fin or longitudinal body 8, may support the 95 weight of the entire flare without the use of the ordinary wings now so commonly employed in aeroplanes.

The vacuum chamber may be provided 100 with air buffers 15 for the same purpose as

the air buffers 29 in my Patent No. 1,779,005.

When desired short or dwarf wings 16 may extend outwardly from the vacuum chamber sides and carry ailerons 17 for the usual purposes. Where the area of the vacuum chamber, including the spread across the flares, is sufficient to sustain the vehicle the dwarf wings 16 are made only large enough to act as supports for the ailerons 17. Furthermore the length of the ailerons from fore to aft is very much less than the length of the vacuum chamber, as will be seen by reference particularly to Figures 1 and 2.

In interpreting the scope of this invention and the claims hereunto appended, I desire it understood that the term "body" is not to be limited to any particular type of body, be it open cockpit or cabin type, or be it simply a blind fuselage with a cabin suspended beneath, the gist of the present invention being in the provision of the vacuum chamber of such area, design and construction that it will furnish the greater part, if not all, of the lifting power of the machine, making it possible to wholly eliminate the use of wings or to use only dwarf wings as described.

From the foregoing description, taken in connection with the accompanying drawings, it is thought that the complete construction, operation and advantages of my invention will be readily understood to those skilled in the art.

What I claim is:

- 35 1. In aeroplanes, a body having a tail end provided with steering rudders and elevators, an open top chamber located above said body, the walls of said chamber being arranged to deflect the air currents so as to produce an area of low pressure over said chamber, the side walls of said chamber being flared and extended laterally and beyond the body to serve in lieu of wings.
- 40 2. In aeroplanes, a body having a tail end provided with steering rudders and elevators, an open top chamber located above said body, the walls of said chamber being arranged to deflect the air currents so as to produce an area of low pressure over said chamber, the side walls of said chamber being flared and extended laterally and beyond the body to serve in lieu of wings, and a propelling mechanism including a propeller located at the front end of said body.
- 45 3. In aeroplanes, a body having a tail end provided with steering rudders and elevators, an open top chamber located above said body, the walls of said chamber being arranged to deflect the air currents so as to produce an area of low pressure over said chamber, the side walls of said chamber being flared and extended laterally to serve in lieu of wings, said open top chamber having an air deflecting nose at the front and being

connected with said body by a central longitudinal fin.

4. In aeroplanes, a body having a tail end provided with steering rudders and elevators, an open top chamber located above said body, the walls of said chamber being arranged to deflect the air currents so as to produce an area of low pressure over said chamber, the side walls of said chamber being flared and extended laterally to serve in lieu of wings, a propelling mechanism including a propeller located at the front end of said body, said open top chamber having an air deflecting nose at the front and being connected with said body by a central longitudinal fin. 75

5. In aeroplanes, a body having a tail end provided with steering rudders and elevators, an open top chamber located above said body, the walls of said chamber being arranged to deflect the air currents so as to produce an area of low pressure over said chamber, the side walls of said chamber being flared and extended laterally to serve in lieu of wings, said open top chamber having an air deflecting nose at the front and being connected with said body by a central longitudinal fin. 80

6. In aeroplanes, a body having a tail end provided with steering rudders and elevators, an open top chamber located above said body, the walls of said chamber being arranged to deflect the air currents so as to produce an area of low pressure over said chamber, the side walls of said chamber being flared and extended laterally and beyond the body to serve in lieu of wings, and dwarf wings with ailerons extending laterally from said chamber. 100

7. In aeroplanes, a body having a tail end provided with steering rudders and elevators, an open top chamber located above said body, the walls of said chamber being arranged to deflect the air currents so as to produce an area of low pressure over said chamber, the side walls of said chamber being flared and extended laterally and beyond the body to serve in lieu of wings, a propelling mechanism including a propeller located at the front of said body, and dwarf wings with ailerons extending laterally from said chamber. 110

8. In aeroplanes, a body having a tail end provided with steering rudders and elevators, an open top chamber located above said body, the walls of said chamber being arranged to deflect the air currents so as to produce an area of low pressure over said chamber, the side walls of said chamber being flared and extended laterally to serve in lieu of wings, said open top chamber having an air deflecting nose at the front and being connected with said body by a central longitudinal fin, 115

and dwarf wings with ailerons extending laterally from said chamber.

9. In aeroplanes, a body having a tail end provided with steering rudders and elevators, 5 an open top chamber located above said body, the walls of said chamber being arranged to deflect the air currents so as to produce an area of low pressure over said chamber, the side walls of said chamber being flared and 10 extended laterally to serve in lieu of wings, a propelling mechanism including a propeller located at the front end of said body, said open top chamber having an air deflecting nose at the front and being connected with 15 said body by a central longitudinal fin, and dwarf wings with ailerons extending laterally from said chamber.

10. In aeroplanes, a body having a tail end provided with steering rudders and elevators, 20 an open top chamber located above the body, the walls of said chamber being arranged to deflect the air currents so as to produce an area of low pressure over said chamber, the side walls of said chamber being flared and 25 extended laterally to serve in lieu of wings, said open top chamber having an air deflecting nose at the front and being connected with said body by a central longitudinal fin, a portion of which is cut out, said body having 30 top openings registering with said cut out portion, and dwarf wings with ailerons extending laterally from the said chamber.

11. In aeroplanes, an elongated body having a tail end provided with the usual steering 35 rudders and elevators, an elongated open top chamber located over said body and connected with the same along the mid-vertical plane, the side walls of said chamber being curved upwardly and laterally extended beyond the body to serve in lieu of wings, the 40 front end of said chamber having a downwardly and rearwardly inclined nose portion and an upwardly and rearwardly inclined nose portion to deflect the air currents so as 45 to produce an area of low pressure over said chamber, substantially as shown and described.

12. In aeroplanes, an elongated body having a tail end provided with the usual steering 50 rudders and elevators, an elongated open top chamber located over said body and connected with the same along the mid-vertical plane, the side walls of said chamber being curved upwardly and laterally extended beyond the body to serve in lieu of wings, the 55 front end of said chamber having a downwardly and rearwardly inclined nose portion and an upwardly and rearwardly inclined nose portion to deflect the air currents so as 60 to produce an area of low pressure over said chamber, a propeller mounted at the front end of said body beneath said nose, the spread of said chamber and the length of said chamber being so designed to produce approximately the full lifting power of the plane. 65

13. In aeroplanes, an elongated body having a tail end provided with the usual steering rudders and elevators, an elongated open top chamber located over said body and connected with the same along the mid-vertical plane, the side walls of said chamber being curved upwardly and laterally extended to serve in lieu of wings, the front end of said chamber having a downwardly and rearwardly inclined nose portion and an upwardly and rearwardly inclined nose portion to deflect the air currents so as to produce an area of low pressure over said chamber, a propeller mounted at the front end of said body beneath said nose, the spread of said chamber and the length of said chamber being so designed to produce approximately the full lifting power of the plane, and dwarf wings extending laterally from said chamber for the purposes described. 70 75 80 85
